MACHINE FOR MAKING PHOTO PRINTS ON
PRINTING CYLINDERS

Jules J. Brell, New York, N. Y.

Application February 12, 1935, Serial No. 6,179

11 Claims. (Cl. 95—73)

The object of the present invention is to provide a machine for making photographic prints on printing cylinders such as used in the textile printing industry wherein a design is photographically reproduced upon a printing cylinder, the latter then being etched so that the design is generally in intaglio or in relief in the case of other classes of printing, as, for example, printing of some classes of wall paper, oil cloth, etc.

10 The object of the invention is to provide a machine which will insure exact registration of the ends of the design upon the printing cylinder so that the design will be continuous without any observable line of joining of the design ends.

15 A further object of the invention is to provide a machine which will readily receive rollers of different lengths and which is adapted for rollers of various diameters.

20 A further object of the invention is to provide novel means for insuring firm contact between the film and the metallic cylinder throughout the printing operation without the possibility of slip.

25 These and other objects will hereinafter appear.

25 The invention will be described with reference to the accompanying drawings in which:—

Fig. 1 is a side elevation of a machine embodying the invention.

Fig. 2 is a plan view of the machine, the central portion thereof being broken away for clearer illustration.

Fig. 3 is a plan view showing the ends of the film, end clamping means and elastic tension means.

35 Fig. 4 is a side elevation thereof.

Fig. 5 is a longitudinal section on the line 5—5, Fig. 1, looking in the direction of the arrow and turned in perspective.

40 Referring to Figs. 1 and 2, I have shown the frame section 1 supported on legs 2. Frame section 1 is box-like in form with a central division web 3. At each end of web 3 there is formed a heavy transverse boss 4, each boss being provided with an aperture to receive a shaft 5, ball bearing members 6 being seated in the boss at the ends thereof and surrounding shaft 5. On an end of each shaft is clamped a sprocket wheel 7 by means of which the shafts will be rotated.

45 50 A frame section identical with that just described is provided at the opposite side of the machine and the drawings show the elements bearing the corresponding numbers.

55 Intermediate shafts 5 is a spacer and supporting shaft or bar 8 having shoulders 9 abutting

webs 3, the ends of the shafts being supported in bearing bosses 9 and receiving nuts 10.

The shafts 5 receive pairs of annular members for the printing cylinder which is to receive the photographic print. Each annular support comprises a wheel-like member 11 having a peripheral flange 11x and a grooved hub 11xx. The groove in the hub of each annular support receives a yoke 12 carried by yoke shifting member 13 supported on shaft 8.

10 Sprocket wheel 7 receives a chain 15 which is led over an additional sprocket wheel 16 on a shaft 17 carrying a sprocket wheel 18 to which will be led power from a motor or other prime mover. Intermediate its length the sprocket wheel passes 15 over an adjustable tension sprocket 19 on a stud shaft 20. Stud shaft 20 passes through a vertical slot formed in web 3 and at its inner end carries a nut 20x. By loosening the nut, shaft 20 may be moved up and down to adjust the tension 20 on chain 15.

Bolted upon each of the frame sections is a bracket 21 having spaced arms 21x between which is pivoted at 22 an arm 23 carrying at its end a bearing boss 23x apertured to receive a shaft 24 25 and formed with a seat to receive a ball bearing member 25 surrounding the shaft. Shaft 24 is formed with an annular head secured within a light hollow idler roller 26.

Spaced arms 23 are held in spaced relationship 30 by a spacer bar 27, the reduced threaded ends of which receive holding nuts 28, each nut abutting one of the arms 23, the reduced ends preferably projecting to provide hand grips.

Each arm 23 is apertured to receive a latch pin 35 29, the latch pin passing through aligned apertures in the arm 21x of each bracket 21, as shown more particularly in Fig. 2.

Mounted to throw a beam of light in substantially a horizontal path, is a light hood 30, which 40 at its front is formed with a beam aperture 31. In practice, beam aperture plates 32 each having a beam slot 32x of the desired width, will be inserted in the hood, as shown more particularly in Fig. 5. The width of the beam slot will determine the length of exposure given to the light sensitive emulsion on the printing roller, (the latter being indicated at 33).

Shaft 5 is longitudinally grooved to receive a key 40 secured in position by screws 41, and 50 entering a corresponding keyway, formed in the hubs of the appropriate annular supports on said shaft 5.

In the operation of the device, set screws 44 will be loosened and yokes 12 will be moved to 55

adjust the annular supports 11 in accordance with the length of a metallic cylinder to receive the photographic print. The cylinder will then be placed in position intermediate the two pairs 5 of annular supports, the ends of the cylinders resting against the peripheral flanges 11x. Set screws 14 will then be tightened to hold the annular supports in such adjusted position. A flexible film bearing an image of the desired 10 width and of a length the exact circumferential area of the metallic cylinder, will be placed in position. The film will be brought around the metallic cylinder as shown more particularly in Fig. 1 and its ends will be connected through 15 the intermediary of yielding tension means. Each end of the film receives a clamping bar comprising a lower section 34 and an upper section 34x between which is passed the end of the film, the sections then being connected by means of 20 screws 35. The clamping bar is formed on the upper member 34 with threaded apertures to receive buttons 36. The button of one clamping bar is connected to a corresponding button of a second clamping bar by a plurality of heavy 25 rubber bands 37, each band having at its opposite ends a bracket 38 formed with an aperture 39 to be received by any suitable button of the appropriate clamping bar.

During the connection of the ends of the film, 30 latch pins 20 will be withdrawn and arms 23 dropped so as to move idler 26 toward the frame of the machine. When the connection of the film ends has been completed, arms 23 are swung upwardly, thus imparting tension upon the bands 35 and the arms secured in position by restoring the latch pins 29. Ordinarily twenty-five or thirty pounds pull will be given to the film so that the latter will conform exactly with the annular surface of the cylinder

40 It will be noted that at this point the film is in contact with the printing cylinder over substantially half of the surface area thereof. Now that power is applied and the annular cylinder supporting members 11 rotated, the heavy cylinder, usually of copper and weighing up to 450 pounds, will be given a very slow rotation which may be one inch of movement in three minutes. The beam of light projected upon the design area of the film indicated between the points a—a will 45 expose the image upon the sensitized surface of the cylinder and when the rear end of the image area comes within the range of the beam of light it will lie exactly in register with the end previously exposed upon the cylinder so that the entire 50 circumference of the cylinder will have the image exposed thereon with a uniformly equal timing of the exposure. This timing will be in accordance with the speed of the emulsion on the cylinder, the density of the film and other conditions met with in usual practice. Thus by adjusting the width of the light aperture, the time of exposure may be adjusted relatively to the speed 55 of the emulsion and other conditions.

Having described my invention, what I claim 60 and desire to secure by Letters Patent, is as follows:—

1. In a machine for making photo prints on printing cylinders, means for supporting a cylinder, means adapted to impart rotation to the cylinder, clamping members for each end of a flexible film, yielding tension means for connecting said clamping members to form with the film an endless belt, a support for said tension means permitting movement of the tension means relatively to said support for simultaneous rota- 75

tion of the cylinder and corresponding movement of the endless belt formed by the film and tension means, and means for throwing a beam of light upon a film held adjacent the cylinder by said tension means. 5

2. In a machine for making photo prints on cylinders, means for supporting a cylinder, means for imparting rotation to the cylinder, clamping members for each end of a flexible film, yielding tension means for connecting said clamping members, a rotary support over which the tension means may be led for movement relatively to the support and latching means for holding the support in position to actuate said tension means, release of the latching means permitting the support to move to such position as to release the tension means from normal action 10

3. In a machine for making photo prints on printing cylinders, means for supporting a cylinder, means for imparting rotation to the cylinder, a flexible film carried over the cylinder and having its ends spaced a substantial distance from the cylinder and from each other in a plane transversely of the face plane of the film, clamping members for each end of the film, yielding 20 tension means connecting said clamping members and a roller over which said yielding means are passed so that said yielding means is given a movement relatively to the roller during the rotation of the cylinder. 30

4. A machine constructed in accordance with claim 3, in combination with latching means for holding the roller in position to activate said tension means, release of the latching means permitting movement of the roller to such position that the tension means is released from normal action. 35

5. In a machine for making photo prints on cylinders, means for frictionally supporting a cylinder comprising spaced rotary members, 40 means for driving said rotary members to impart rotation to the cylinder, clamping means for each end of a flexible film, yielding tension means for connecting said clamping members and a support for said tension means permitting movement of the tension means relative to the support during the rotation of the cylinder. 45

6. In a machine for making photo prints on printing cylinders, a frame, spaced rotary members carried by the frame and adapted to receive 50 a cylinder between them, means for driving said rotary members, an idler roll supported by the frame and adapted to receive members connecting the ends of a flexible film led over the cylinder, and means for relatively adjusting the position of the idler relatively to said rotary members. 55

7. In a machine for making photo prints on printing cylinders, a frame, two pairs of annular frictional supports, each pair adapted to engage opposite ends of a cylinder placed between 60 the pairs, means for imparting rotation to an annular support whereby a cylinder resting thereon is given rotation, means for supporting one section of a film structure passing at a second section over the surface of a cylinder held by 65 said annular frictional supports, and means for throwing a beam of light.

8. A machine constructed in accordance with claim 7, in which each pair of annular film supports comprises two supports adjustable toward 70 and from each other to engage cylinders of various lengths.

9. A machine for making photo prints on cylinders in accordance with claim 7, in which the pairs of annular film supports comprise 75

flanged wheel-like members, the supports of each pair being adjustable toward and from each other to bring the flanges into abutment with the ends of a cylinder.

5 10. A machine constructed in accordance with claim 1, in which the support for the tension means comprises an idler roller, pivoted arms carrying said idler roller, and permitting movement of the latter toward and from the supporting means for the cylinder, and latching means for holding the arms in adjusted position.

10 11. In a machine for making photo prints on

printing cylinders, means for rotatably supporting a cylinder, a flexible film having thereon an image equivalent in area to the circumferential area of the cylinder, the film being carried over and in abutment with an arcuate section of the 5 cylinder, means for imparting tension upon the film, and means for simultaneously rotating the cylinder and moving the film in synchronism with said rotation during the exposure of said image area of the film to light.
